UNITED STATES PATENT OFFICE.

ALFRED L. CHAPMAN, OF LOS ANGELES, CALIFORNIA.

FOLDING RUNNING-BOARD RACK.

Application filed June 8, 1928. Serial No. 223,789.

My invention relates to automobile accessories and more particularly to a rack device for use on running-boards.

The primary object of my invention is to provide a detachable rack which readily may be attached to the running-board of an automobile so as to be available for holding packages, traveling bags and the like.

A further object is to provide a folding running-board rack which readily may be adjusted to an erect position for use or may be folded so as to leave a practically clear running board.

Other objects and advantages will appear hereinafter and while I show herewith and will describe a preferred form of construction, I desire it to be understood that I do not confine my invention to such preferred form but that various changes and adaptations may be made therein without departing from the spirit of my invention as hereinafter claimed.

Referring to the drawings which accompany this specification and form a part thereof,

Fig. 1 is a view in perspective of an automobile running-board having my folding rack mounted thereon, the rack being in its erect or expanded condition.

Fig. 2 is a plan view of the folding rack shown in Fig. 1, by itself, in its folded condition.

Fig. 3 is an enlarged sectional view of one end of the folding rack shown in Fig. 2, the section being taken on line 3-3 of that figure.

Fig. 4 is a fragmentary side view of the opposite end of the folding rack from that shown in Fig. 3, and of a running-board to which it is attached.

Fig. 5 is a transverse sectional view of the folding rack and running-board shown in Fig. 4, taken on line 5-5 of that figure.

Considered more in detail, the drawings will be seen to show a metal channel 10 corresponding in length to the running-board 11, on which it is mounted, and having clamps 12, fixed adjacent the ends thereof adapted to grip the edges of the running-board so as to hold channel 10 flush with the outer edge thereof. The web plate 13 of channel 10 is provided with apertures 14 through which dust and dirt, such as may work to the bottom of the channel, may drop out therefrom. The outer flange 15 is

provided with a longitudinal slot 16 slightly above web plate 13 and adjacent one end of the channel, preferably the front end. The inner flange 17 of the channel has foot-plates 18 fastened thereto in line with the doors 19 of the automobile, the length of said foot-plates being approximately equal to the width of doors 19, their width being equal to the width of the running board, less that of channel 10, and their thickness corresponding to the outside depth of channel 10, so that they fill in the spaces between the channel and the doors, flush with the upper edges of flanges 15 and 17.

Clamps 12 are each formed of a front bracket 20, fastened to outer flange 15 of channel 10, said front bracket being bent to form an offset lug 21 under the running-board, a bolt 22 extending through said lug 21, said bolt having a squared head 23 and a collar 24 thereon, the former on the outer side and the latter on the inner side of said lug 21, and a complementary rear bracket 25, having an up-turned lug 26 adapted to engage the inner edge of a running board and an offset lug 27 adapted to receive the screw-threaded end 28 of bolt 22, as shown in Fig. 5. It is obvious that by using a wrench on head 23 the brackets may be tightened so as to hold channel 10 and foot-plates 18 securely attached to the running-board or may be loosened so as to permit the removal of the channel and foot-plates therefrom.

A sliding bar 29, somewhat shorter than channel 10 and of a width to fit loosely between its flanges 15 and 17, is laid in channel 10, said sliding bar having a series of hinge plates 30 attached to its upper side, in uniformly spaced relation to each other. To each of said hinge plates 30 is attached a flat bar 31, of equal width with sliding bar 29 and of a length approximately equal to the distance between said hinge plates 30, by a hinge-pin 32 and a similar but somewhat shorter bar 33 is attached to the free end of each bar 31 by a hinge pin 34, the other end of said bar 33 being attached to a transverse pivot pin 35 in channel 10 with its ends fixed in flanges 15 and 17 thereof. Hinge pins 32 and 34 being parallel to pivot pins 35, bars 31 and 33 are caused to turn thereon, when sliding-bar 29 is shifted longitudinally, so as to swing upwardly and spread apart, as shown in full line in Fig. 1, 110

and indicated in dotted lines in Fig. 3, or to swing downwardly and fold into channel 10, as shown in full lines in Figs. 2 and 3.

A shifting knob 36, with a shank 37 extending through slot 16, is attached to sliding bar 29 and a spring 38 adapted to snap across slot 16 in front of shank 37 so as to hold knob 36 and sliding plate 29, to which it is attached, in their expanding position, is attached to outer flange 15 as shown in Fig. 4. The tension of spring 37 is such that it will yield and permit shank 36 to pass when a strong pull on knob 35 is exerted against it to collapse and fold the rack.

The operation of the folding rack thus constructed is evident from the description given. When expanded, a series of pairs of oppositely inclined bars 31 and 33 are erected adjacent the outer edge of the running board so as to form a retaining rack thereon, as shown in Fig. 1, and when collapsed the running-board is left clear except for the channel 10 and foot plates 18 which occupy but little space, all the rack parts being made of comparatively thin material.

Having thus illustrated and described my invention, I claim:

1. A running-board rack comprising a sliding-bar adapted to be mounted adjacent the outer edge of a running-board, so as to be slidable longitudinally thereon; a series of pairs of pivotally connected bars, one of which is pivotally attached to said sliding-bar and the other of which is pivotally attached to the running-board; means for shifting said sliding-bar and means for holding it in its shifted position.

2. A running-board rack comprising a channel adapted to be detachably fixed on a running-board, adjacent the outer edge thereof; a sliding-bar mounted in said chan-

nel so as to be slidable longitudinally therein; a series of pairs of pivotally connected bars pivotally attached to said sliding-bar and to said channel, so as to swing downwardly into a folded position within said channel or upwardly into an erect expanded position, according as said sliding bar is shifted forwardly or backwardly; means for shifting said sliding-bar forwardly or backwardly and means for holding said sliding bar in its shifted position.

3. A folding running-board rack comprising a channel adapted to be mounted on a running-board; clamps attached to said channel so as to hold it on a running-board, adjacent the outer edge thereof; a sliding-bar mounted in said channel so as to be slidable longitudinally therein; a series of pairs of pivotally connected bars, one of which is pivotally attached to said sliding bar and the other of which is pivotally attached to said channel; means for shifting said sliding bar forwardly or backwardly and means for holding said sliding bar in its shifted position.

4. In combination with an automobile running-board, a folding rack comprising a channel mounted thereon adjacent the outer edge thereof; clamps attached to said channel and adapted to detachably hold it in position on the running board; a sliding-bar mounted in said channel so as to be slidable longitudinally therein; a series of pairs of pivotally connected bars one of which is pivotally attached to said sliding-bar and the other of which is pivotally attached to said channel; a shifting knob attached to said sliding-bar and a retaining spring adapted to hold said sliding-bar in its shifted position.

ALFRED L. CHAPMAN.
